(57) **CLAIM**

The ornamental design for a slicing guide apparatus, as shown and described.

DESCRIPTION

FIG. 1 is an isometric view of the slicing guide apparatus;
FIG. 2 is the front view of FIG. 1;

FIG. 3 is the left side view of FIG. 1;

FIG. 4 is the top view of FIGS. 1; and,

FIG. 5 is the bottom view of FIG. 1.

The slicing guide apparatus aids in the slicing of lettuce and other perishable and non-perishable food items.

1 Claim, 5 Drawing Sheets

FIG. 1

FIG. 2

FIG. 3

FIG. 4

FIG. 5
